The ornamental design for a smart key for vehicles, as shown and described.

(30) **Foreign Application Priority Data**

DESCRIPTION

Mar. 27, 2019 (KR) 30-2019-0014013

1. Smart key for vehicles

(51) LOC (13) Cl. **14-03**

1.1 : Perspective

(52) U.S. Cl.

1.2 : Front

USPC **D13/168**

1.3 : Back

(58) **Field of Classification Search**

1.4 : Left

USPC D10/104.1, 106.1, 106.9; D8/347;

1.5 : Right

D13/168; D14/435, 218; D12/400

1.6 : Top

CPC G07C 2009/00984; E05B 19/0085

1.7 : Bottom

See application file for complete search history.

1.8 : Reference

(56) **References Cited**

Reproduction 1.8 is a reference view showing a state of use in which a smart key is connected to a docking station; the broken lines showing portions of the article and the docking station in reproduction 1.8 form no part of the claimed design.
